US0D1060351S

(12) **United States Design Patent** (10) Patent No.: **US D1,060,351 S**
(45) Date of Patent: ** Feb. 4, 2025

(54) **PEDESTAL SCANNER**

- (71) Applicant: **Amazon Technologies, Inc.**, Seattle, WA (US)
- (72) Inventors: **Alexander Digby Williams**, Seattle, WA (US); **Michael Ryan Lostoski**, Seattle, WA (US); **Spencer Ralph Dodge**, Covington, WA (US); **Dwight Walter Jones**, Seattle, WA (US); **Aaron James Piazza**, Lake Forest Park, WA (US); **Sara Elizabeth Stille**, Seattle, WA (US)
- (73) Assignee: **Amazon Technologies, Inc.**, Seattle, WA (US)
- (**) Term: **15 Years**
- (21) Appl. No.: **29/931,759**
- (22) Filed: **Mar. 8, 2024**

Related U.S. Application Data

- (63) Continuation of application No. 29/843,292, filed on Jun. 20, 2022.

(57) **CLAIM**

The ornamental design for a pedestal scanner, as shown and described.

DESCRIPTION

FIG. 1 is a top, front, left-side perspective view of a pedestal scanner;

FIG. 2 is a top, front, right-side perspective view thereof;

FIG. 3 is a bottom, back, left-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof; and,

FIG. 9 is a bottom view thereof.

The dashed broken lines depict portions of the pedestal scanner that form no part of the claimed design.

1 Claim, 9 Drawing Sheets
